UNITED STATES PATENT OFFICE.

JAMES E. SMITH, OF NEW YORK, ASSIGNOR OF THREE-EIGHTHS TO A. W. LE FURGE AND FRANCIS BUCKLEY, BOTH OF BROOKLYN, N. Y.

GAS-GENERATOR.

SPECIFICATION forming part of Letters Patent No. 340,634, dated April 27, 1886.

Application filed August 25, 1885. Serial No. 175,311. (No model.)

To all whom it may concern:

Be it known that I, JAMES E. SMITH, a citizen of the United States, residing at New York, in the county of New York and State 5 of New York, have invented a new and useful Improvement in Gas-Generators, of which the following is a specification, reference being had to the accompanying drawings.

My invention has relation to improvements 10 in gas-generators; and the novelty consists in the peculiar construction and combination, arrangement, and adaptation of the various parts, substantially as hereinafter fully set forth, and specifically pointed out in the claims.

15 I have shown an embodiment of my invention in the accompanying drawings, in which Figure 1 is a side elevation of my improved generator, showing the connections with a supply-tank and the regulating-valves. Fig. 2 is a transverse cross-sectional view through the water-chamber and the oil or mixing chamber. Fig. 3 is a vertical section of the oil-chamber supply-valve; and Fig. 4 is a 20 sectional elevation through the water-chamber regulating-valve. Fig. 5 is a longitudinal central section through the retort or mixing chamber. Fig. 6 is a plan view of the oil-valve.

Like letters of reference in the several drawings denote corresponding parts.

Referring to the drawings, A designates my improved generator. B designates an elevated supply-tank, and C designates the connections between said generator and tank.

35 The generator A consists, essentially, of two chambers, D E, one of which, D, constitutes the water and steam chamber, and the other chamber, E, the oil and mixing chamber or retort. These chambers are preferably 40 rectangular in form and are of different sizes, the water-chamber D being larger than the oil chamber or retort E; but these forms and proportions may be varied without departing from the principle or sacrificing the advantages of my invention. The chambers are also 45 preferably arranged alongside of or parallel with each other, and are fixed or secured upon a base-plate, F.

The water-chamber is provided with a 50 threaded socket, a, in one of its end walls, in

which is screwed the end of a pipe, C, connecting at its opposite end with the supply-tank B, the said socket being preferably arranged near the lower end of one of the end walls of the chamber D, as shown.

55

The two chambers D E are connected together by means of a pipe, b, or other well-known device, arranged near the upper edges of said chambers, and near one end thereof, as shown, thus providing for the admission of 60 steam, which is generated in the water-chamber D, into the oil or mixing chamber E.

The oil chamber or retort E is provided with a seat or socket, e, having an interior thread for the reception of one end of the supply-pipe C, connected with the tank B.

In Fig. 1 of the drawings I have shown the tank B as divided by a vertical partition-wall, B', to provide two chambers, B' B'', for the reception of oil and water, respectively; but I 70 would have it understood that I do not wish to limit myself to the particular form of supply-tank herein shown, as two separate and independent tanks for the oil and water may be employed, or a tank of other construction. 75

The oil-chamber E has a series of partitions or dividing-walls, E', and arranged in an inclined position in the following manner: The upper or first wall is arranged a short distance from the top of the chamber and immediately 80 beneath the supply-port e, said partition extending in an inclined position longitudinally of the chamber to a point a short distance from the opposite end wall, to which it is secured or formed integral therewith. This peculiar 85 arrangement of the first or upper partition provides a longitudinal passage, f, and a short vertical opening or passage, f', at the end, between the terminal end of the first or upper partition and the end wall of the chamber. 90 The second partition, E', is inclined in an opposite direction to the first or upper partition, and extends longitudinally of the chamber beneath said upper partition and from the end wall opposite to which said upper partition 95 starts, thus bringing the lower end of said second partition a short distance below the front end of the upper partition and from the opposite end wall to which it starts. The remaining partitions E' are arranged in a similar 100

manner with relation to each other and the chamber or receptacle, said partitions being inclined in opposite directions from each other, terminating a short distance from opposite end 5 walls of said chamber, and arranged beneath each other and longitudinally of the chamber from the side walls thereof, thus providing the passages $f f'$, which communicate with each other and permit the free mingling of the two 10 gases arising from the generation of steam and carbon gas.

In practice I prefer to cast the oil chamber or retort with the dividing-partitions to form or provide the flues, and I have found by experiment that the following arrangement and proportions have given good results: The upper or first partition is arranged one-half an inch from the upper wall of the chamber, and then inclined downwardly toward its opposite 20 end, so that it will fall one inch from the upper wall of the chamber, thus giving a "drop" or incline of one-half an inch. The elevated end of the next or succeeding partition is arranged one inch from the upper wall and on 25 the plane of terminal end of the upper partition, and then inclined forwardly, so that its terminal end will be one inch from the elevated end of the first or upper partition, or one inch and a half from the upper wall of the 30 chamber, and so on with the remaining partitions. In the drawings I have shown five of such partitions arranged beneath each other and in the manner described; but I would have it understood that the proportion and 35 number of partitions can be varied to suit the capacity and size of the apparatus without departing from the spirit of my invention.

By the peculiar arrangement of partitions heretofore described I secure flues or passages 40 of alternate widths, one end thereof being enlarged and the opposite end contracted to perhaps half the diameter of the larger expanded end. This arrangement of flues causes the 45 gases to become thoroughly commingled and mixed by reason of the tortuous passage through which they traverse, and by reason of the expanded and contracted ends of the flues the gases are caused to expand and contract when 50 passing along one flue and into the next adjacent flue, as will be very readily understood from the foregoing description, taken in connection with the drawings.

By the enlarged and contracted ends of the longitudinal flues the two gases—steam and carbon gas—are caused to alternately expand and contract, and by reason of such expansion and contraction the two gases are thoroughly and intimately mixed and commingled together when passing through the flues of the 55 generator. The inner or adjacent wall of the oil-chamber to the water-chamber is provided with a perforation or a series of perforations at its bottom to permit the gas to escape from the mixing-chamber, or the oil from the reservoir and chamber to flow out upon the base-plate, the latter operation being performed to 60 heat the two chambers to a high degree to

generate the steam in the water-chamber and the carbon-gas in the oil-chamber from the water and oil respectively.

I have shown the water-chamber D as elevated above the bottom or base plate on flanges $g g$, arranged at each end thereof, thus permitting the oil from the oil or mixing-chamber to flow beneath the said water-chamber, and when said oil is ignited by dropping a lighted match onto the surface thereof the heat arising from its combustion will elevate the temperature of such chambers and base-plate to a very high degree to consume the oil flowing into said oil-chamber and convert the water in the chamber D into steam. As soon as the steam is generated it passes from the water-chamber D into the mixing-chamber through the connecting-pipe and commingles with the carbon gas 80 in said mixing-chamber in the manner hereinbefore described and flows onto the base-plate, where it may be consumed to heat said base-plate, or conducted by pipes or other means for illuminating purposes.

By heating the mixing-chamber to a very high degree and causing the two gases to traverse the tortuous and extended passages in the flues, the dividing-walls of which are also heated, the steam from the water-chamber is 95 heated to a very high degree by impinging against the heated walls and partitions of the retort while passing through the same, and by reason of the gases from the oil and steam being in contact throughout their passage through 100 the retort they are intimately commingled and provide a hydrocarbon gas for consumption by the time that it escapes from the mixing-chamber.

My improved gas-generating apparatus is 105 especially adapted for use as a means for heating water, cooking food, and other like domestic purposes, and for apartment-heating; but it can be used with equal advantages in a great variety of ways.

In Figs. 3 and 6 of the drawings I have shown a valve especially adapted for use in connection with the supply-pipe to the oil-chamber and tank of the apparatus, and in Fig. 4 a regulating-valve is shown for use in 115 connection with the water-chambers, the peculiar construction and arrangement of the various parts of which are as follows:

The regulating-valve H to the oil-chamber comprises a shell, H' , preferably tapering in form, and having educt and supply ports $h h'$, arranged on opposite sides of the shell, and one below the other, said ports having bosses h^2 , provided with threads, in which the sections of the supply-pipes are connected. The 120 plug H^2 is also made tapering in form, and is rotatively secured or mounted in the shell, the lower end thereof having a shoulder, h^3 , and an internal screw-threaded portion, h^4 , in which works a bolt, i , adapted to hold the 125 plug in position, a washer, i' , being interposed between the bolt i and the lower end of the shell. The bolt bears against the washer, which 130 impinges against the shell, and said washer

rotates with the plug when it is turned in the shell, to permit a supply of oil to flow from the supply tank to the combustion or oil chamber E.

- 5 The plug H² is provided with a longitudinal central bore, j, and at its lower and upper ends opposite to the supply and exit ports it is provided with transverse bores j' j² j³, the lower of which, j', is of larger diameter than 10 either of the upper bores, j² j³, which are also of different diameters, to permit the oil to flow into the supply-pipe C to the oil or mixing chamber in different quantities. For instance, when the larger bore j' is turned to 15 coincide with the exit-port of the shell, a larger quantity of oil will pass through the same from the tank and central longitudinal bore of the plug, and when said plug is turned so that the smaller passage or bore j³ coincides 20 with the exit-port a reduced or smaller quantity of oil is fed to the oil or mixing chamber. The head of the plug projects above the case, and is squared, as at I, for the reception of a turning-wrench or other implement, and the 25 said head is provided with indicating notches J, one of which is longer than the other, so that when the plug is turned to bring one of the notches in alignment with the supply-pipe to the oil-chamber the length of that notch 30 will indicate whether the oil is flowing through the larger or smaller of the bores or passages j' j³.

An important result gained by this peculiarly-constructed valve H is that the quantity of oil can be easily and readily governed and the pressure of the oil in the tank is taken off the oil or mixing chamber pipes and thrown upon the valve itself, the escape-passages of which are of a very small diameter, and the plug of 40 considerable length and of sufficient strength to insure stability.

K designates the water supply-regulating valve, which is designed to operate automatically to feed the proper quantity of water to the 45 water-chamber when the water therein has fallen below the level. The valve comprises a casting, K', preferably cylindrical in form and having heads k, the lower one of which is threaded at its periphery and removably secured in threaded surfaces of the cylinder, as 50 shown in Fig. 4. The removable head is provided on its under surface with a threaded neck or socket, k', having a vertical aperture or passage, k'', which is made tapering, and through this opening or seat passes a valve-rod, l, also made tapering to fit the seat k'', and having at its lower end a disk or valve, l', adapted to normally close the water-passage or valve-seat k''. The rod l passes entirely 55 through the cylinder and works in the valve-seat and an opening, l'', in the opposite head of the cylinder, and is provided at the point where it emerges from the seat k'' with a float, m, preferably of cork or other suitable material and rigidly secured thereon. The cylinder is provided in one of its vertical walls with a supply pipe and port which commun-

cates with the water chamber D. The upper cylinder-head may have an air-port, as shown at o.

M designates an elbow and valve-chamber having interior-threaded portions or arms, one of which engages with the threaded neck k' of the cylinder or shell head, while the other arm is connected to the supply-pipe to the water-chamber of the tank B or other supply, as will be readily understood. When the water falls or descends below the water-line in the steam generator or chamber D, it also descends in the pipe C and permits the valve, its rod, and the 80 float to descend and the water to pass from the water-chamber or cylinder until the proper quantity has been fed to the water-chamber D and the float rests on the lower cylinder-head.

An important result is accomplished by 85 constructing the valve and rod as described, namely: the proper supply of water is automatically fed to the water-chamber when the water descends below a given line. All leakage of water is prevented from the cylinder 90 by reason of the tapering valve-rod and its seat and the valve-disk impinging against the outer face of the neck k', as is obvious. The valve may have an elastic ring or packing, n, arranged to bear against the neck k', as is ob- 95 vious.

The operation of my invention is as follows: When it is desired to heat the chambers, a supply of oil is allowed to pass from the oil tank or reservoir by turning the plug of the valve 100 so that it can pass through the pipe into the oil chamber and flow through the same on the inclined partitions thereof into the chamber or base-plate through the apertures in the side wall of said oil-chamber. A lighted match is 105 then dropped onto the surface of the oil, which ignites and heats the oil and water chambers to a very high degree, water having been first admitted or always remaining in the water-chamber. The water is converted into steam, 110 and a supply of oil is admitted to the oil-chamber in a proper quantity, and is there converted into carbon gas and commingles with the steam flowing into said oil-chamber. The 115 gases are thus thoroughly and intimately mixed and commingled in the mixing-chamber in the manner hereinbefore described, and the steam is at the same time reduced from a wet state to a highly elastic and dry state.

The apparatus is simple, strong, and durable 120 in construction, thoroughly effective and automatic in operation, and is cheap of manufacture.

Any quality or degree of any kind of oil can be used, some with perhaps better results, and 125 I find by experiment that four gallons of water are consumed to one gallon of oil.

Having thus fully described my invention, what I claim as new, and desire to secure by Letters Patent, is—

1. In a gas-generator, a mixing-chamber having a series of longitudinal partitions arranged in inclined alternate directions, a steam-generating chamber, connections between said

chambers, a heating-base, a supply-tank, pipes connecting chambers and tank, an automatic supply-valve in the water-supply pipe, and a regulating-valve in the oil-supply pipe, substantially as described.

2. In a gas-generator, the combination, with the steam and mixing chambers, of a supply tank and pipe and an automatic supply-valve comprising a shell, a valve-rod working in a tapered seat, a valve-disk mounted thereon, a float, and an elbow connected to the valve-seat, all arranged and adapted to serve as described.

3. In a gas-generator, and in combination with the steam and mixing-chambers thereof, a tank, a supply-pipe to the mixing chamber or retort, and a valve, H, in the retort-supply pipe and comprising a shell having educt and exit ports in different planes, a plug having a longitudinal bore and provided with transverse bores leading from the longitudinal bore to the educt and exit ports of the shell or casing, as set forth.

4. In a gas-generator, the combination of a retort comprising an elongated casing or shell

and longitudinal partitions arranged in horizontal planes and alternately inclined positions, a water-chamber having a steam-space, a heating base or plate on which the retort and chamber are mounted, a tank having oil and water chambers, supply-pipes leading from the chambers of the tank to the water-chamber and the retort, the supply-pipe to the said retort entering the same at one end of the upper flue thereof, a connecting-pipe from the steam-space of the water-chamber and entering the retort near the point of the oil-educt port, an automatic valve in the water-supply pipe, and a regulating-valve in the oil-supply pipe, all arranged to serve substantially as set forth.

In testimony that I claim the foregoing as my own I have hereto affixed my signature in presence of two witnesses.

JAMES E. SMITH.
